(57) **CLAIM**

I claim the ornamental design for a storage rack, as shown and described.

DESCRIPTION

FIG. 1 is a front plan view of the new ornamental storage rack of the present invention.

FIG. 2 is a rear plan view thereof.

FIG. 3 is a top plan view thereof.

FIG. 4 is a bottom plan view thereof.

FIG. 5 is a right side view thereof.

FIG. 6 is a left side view thereof.

FIG. 7 is a front right perspective view thereof.

FIG. 8 is a front plan view of the storage rack of the present invention in an alternative position for use.

FIG. 9 is a rear plan view thereof.

FIG. 10 is a right side view thereof.

FIG. 11 is a left side view thereof.

FIG. 12 is a top plan view thereof.

FIG. 13 is a bottom plan view thereof; and,

FIG. 14 is a front right perspective view thereof.
